CLAIM

The ornamental design for a wrench, as shown and described.

DESCRIPTION

FIG. 1 is a perspective view of a wrench;

FIG. 2 is a left side view of the wrench of FIG. 1;

FIG. 3 is a right side view of the wrench of FIG. 1;

FIG. 4 is a front view of the wrench of FIG. 1;

FIG. 5 is a rear view of the wrench of FIG. 1;

FIG. 6 is a top view of the wrench of FIG. 1; and,

FIG. 7 is a bottom view of the wrench of FIG. 1.
